(57) **CLAIM**

The ornamental design for a mobile phone holder as shown and described.

DESCRIPTION

FIG. 1 is a perspective view of a mobile phone holder showing our new design;

FIG. 2 is another perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof; and,

FIG. 9 is a perspective view of the mobile phone holder of FIG. 1, shown in an alternate position.

The broken lines in the drawings depict portions of the mobile phone holder that form no part of the claimed design.
